UNITED STATES PATENT OFFICE.

SAMUEL H. BROWNING, OF ATLANTA, GEORGIA.

COIL-SPREADING MACHINE.

Application filed February 10, 1925. Serial No. 8,283.

Generically this invention relates to machines for forming or shaping electric conducting coils for electrical apparatus such as armatures and stators for dynamo electric machines, but it more especially comprehends novel improvements on my patent for coil shaping machine, No. 1,297,998. 55

One object of this invention is the provision of an improved coil holder with its vise 10 or gripping members variously adjustable and embodying novel means for maintaining the said members in any desired relative position, so as to firmly grip and hold the wires in a square rectangular bundle during 15 the bending process. 60

Another object of this invention is the provision of an improved end loop clamp or knuckle holder for holding, firmly gripping and properly shaping the loop end of the 20 coil, during the spreading process, the said holder being rotatably adjustable to form a properly shaped knuckle or loop at each end of the coil and at any desired angle with respect to the body of the coil. 65

25 A further important object of this invention is adjustable means for effecting elevation and lowering of the coil ends during the spreading operation. 70

Another important object of this invention 30 is the provision of means for simultaneously and automatically lowering the top or rear coil holders to a point where the bottom of the slot portion of coil grip in rear holders will come to the same distance from center 35 of rotation as the top of the slot portion of coil grip in the front or opposite holders during the spreading operation, thus producing the correct pitch to the side or slot portions of the coil, and returning the said 40 rear holders to their initial position overlying the front or opposite holders when in closed or loading position. 75

A still further object of this invention is 45 the provision of a loop gauge, designed for use in gauging the distance of inside of loop end from side of holder, including means for setting the gauge so that any number of coils may be secured in the holders quickly and expeditiously without further measurements or setting. 80

Other objects of this invention are: to provide a spreader embodying the above specified features, so designed as to produce coils of varying configurations, prevent buckling

of long coils between the holders, capable of 55 being quickly and accurately adjusted, thereby increasing rapidity of operation and effecting economy in labor, simple in construction and manufacturable at a reasonable cost. 60

With these and other objects in view, which will become apparent as the description proceeds, the invention resides in the construction, combination and arrangement of parts, hereinafter more fully described 65 and claimed, and illustrated in the accompanying drawings, in which like characters of reference indicate like parts throughout the several figures, of which:

Fig. 1 is a front perspective view of my 70 improved coil shaping machine;

Fig. 2 is a fragmentary front elevation of the machine illustrated in Fig. 1;

Fig. 3 is an end elevation of the machine in closed or loading position, the arms in 75 open or spreading position being shown in dotted outline;

Fig. 4 is a fragmentary end elevation of the supporting frame showing the pedal and center pull rod; 80

Fig. 5 is a detailed fragmentary sectionized view of one of the rear coil holder supporting bar shifting assembly;

Fig. 6 is a side elevation of one of the coil holders; 85

Fig. 7 is a front elevation of Fig. 6;

Fig. 8 is a rear elevation of Fig. 6;

Fig. 9 is a top plan view of Fig. 6;

Fig. 10 is a top plan view of one of the knuckle holders or end loop gripping members; 90

Fig. 11 is a side elevation of Fig. 10;

Fig. 12 is a side elevation of the loop gauge; and

Fig. 13 is a front elevation of Fig. 12. 95

Fig. 14 is a view of the loop before spreading by applicant's machine; and

Fig. 15 is a view of the loop after having been spread by applicant's machine.

In the illustrated embodiment characterizing this invention there is shown a frame 1 embodying cross bars 2 and 3, diagonal braces 4 and longitudinal bar 5 connecting the two rear legs. Seated on the bars 2 intermediate their length is a longitudinal 100 guide bar 6, and similarly mounted on the cross bars 3 is an upper guide bar 7 with its ends extending beyond the bars 3 and 105

apertured to receive the vertical pull rods 8, the lower ends of said rods carrying the swinging longitudinal bar 9.

Hingedly secured to the rear bar 5 as at 5' is the pedal 10 pivotally connected intermediate its length to the vertical pull rod 11 extending through apertures in the bars 6 and 7, retained in position and limited in its downward movement by the adjustable nut 12, said rod 11 being connected to the movable bar 9 by a pin 13 or other fastening means. Mounted on the frame 1 is the table 14 secured thereto in any suitable manner, and in order to strengthen the bar 7, bracing rods 15 are provided on either side of rod 11 connecting the table 14 and bar 7 secured to the respective parts in any conventional manner.

The bar 9 is normally maintained in elevated position by the duplex coil springs 16 attached to each end thereof and to the table.

A pair of bearing members or "crowfoot" castings 17 are mounted on the table 14 slightly spaced from either end, secured thereto by bolts 18 and adapted to support and provide bearings for the longitudinal center rod 19. A pair of substantially L-shaped oscillating arms 20 and 20' are mounted on the said rod 19 at either end adjacent the members 17 each of the said arms 20 and 20' also being formed with lateral projections 21 and 21' which are connected by the rods 22 and 22'. The arms 20 adapted to oscillate to the front of the center bar 19 are connected by the longitudinal angle bar 23 which is slidably mounted on the rods 22 for vertical adjustment and secured in any desired position by the set screws 24. The arms 20' adapted to oscillate to the rear of the center bar 19 are connected by the rear longitudinal angle bar 23' slidably mounted on the rods 22' for vertical adjustment, but unlike the front anglebar 23 which is fixedly secured to the rods 22 according to any desired adjustment, the rear angle bar 23' is mounted on the said rods 22' adapted for reciprocating movement during the operation of the machine within certain limits, the range of movement being determined by the adjustable spaced collars 25 and 26, respectively, secured to the said rod 22' by set screws 27. The automatic reciprocation of the said bar 23' is effected by the rods *a* extending through the slots *b* in the table 14 which have their upper ends hingedly connected to the angle bar 23' as at *c* with their lower ends extending through swivel bearings *d* secured to the movable longitudinal pull bar 9, and having secured thereon bottom adjustable collars *e* adapted to contact with swivel bearings *d* when spreader is open at finish position of coil. This assures lowering of 23' to contact with

with compression or shock absorbing springs *f* with their lower ends adapted to seat on the said swivel bearings *d* and their upper ends confined by the adjustable collars *g* secured in position by the set screws *h*.

The table 14 and the members 17 are suitably apertured to receive the vertical pull rods 8, the said members 17 acting as guide bearings for the said rods which carry at their upper ends the yoke 28 pivotally secured to the upper ends of the oppositely extending links 29, the lower extremities of the said links being pivotally mounted on the lugs or bolts 30, which are threadedly or otherwise suitably secured to the respective arms 20 and 20' intermediate their length. The members 31 are adapted to space the links 29 from the arms 20 and 20' and may be integrally connected to said arms intermediate their length and apertured to threadedly receive the bolts 30 or they may be in the nature of spacer washers with the bolts 30 threadedly engageable with the said arms, if desired.

Mounted on the said rod 19 on either side of center bearing 32 are the horizontally slidable sleeve members 33 adapted to receive and support the lower ends of vertical rods 34 which are maintained in vertical position by having their upper ends detachably connected to coil springs 35 carried by collars 36 longitudinally slidable on rod 37 supported by the upper ends of upright standards 38 secured to the crowfoot bearing members 17 by bolts 39.

The L-shaped anchoring members 40 are slidably positioned on the vertical rods 34, their limit of vertical adjustment being governed by collar 41 fixedly secured to the said rods by set screws 42, and U-shaped collar 43 secured by set screws 44 in any desired position on the said rods 34. The U-shaped collars 43 carry pinions 45 adapted to mesh with rack 46 fixedly secured to member 40, said pinions being operated by handles 47 for the vertical adjustment of the said members 40.

The loop end gripping members or knuckle holders *A* are adapted to be adjustably positioned on the L-extensions of the members 40 either fixedly or rotatably secured thereto by the set screws 48 extending through the slots 49 which limit the rotatable movement of the said holders. Each of the holders *A* are formed of two complementary parts or plates 50 and 51. Plate 50 constitutes the main body of the holder and is provided with adjusting pin 52 pivotally connected to plate 51 as at 53, said pin being internally threaded to receive the externally threaded adjusting screw 54, for parallelly varying the opening between the gripping faces of the plates 50 and 51, said screw 54 being locked in any desired position by the lock screw 55 inserted in a threaded

opening in plate 50 at right angles to the screw 54. The outer extremity of plate 50 is formed with a right angular hook or horn 56 designed for insertion in the loop 5 end of the coil B and adapted to fit into slot 57 of plate 51 when the plates are in clamped position, for holding the wires intact and rendering it possible to spread the coil B to form the coil C with perfectly 10 shaped loop or knuckle C' at each end, without the necessity of pretaping or dipping to hold wires together. The members 50 and 51 are further retained in closed position by the threaded T-head bolt 58 supported by nut 15 58' which is engaged by the oppositely extending pointed bearing screws 59 and operated by handle 60. When the handle is in a vertical position the T-head of the bolt will pass through a vertical oval slot in rear 20 plate 50, after which a quarter turn to the left causes the T-head to ride up over the several sides of oval hole, thereby exerting a clamping action on a loop which is retained by the loop engaging ends of the 25 clamping plates 50 and 51.

Slidably mounted on each of the horizontal angle members 23 and 23' are a plurality of coil holders or composite vises 61, and as all of these holders are identical, for convenience in description, only one will be described in detail. Coil holder 61 is formed with a triangular opening 62 adapted to receive the angle bar 23 and is secured at any desired position thereon by locking screw 63 30 provided with block or gib 64 for contact with the angle bar 23 on its inner surface and equipped with hand wheel 65 on its outer end. The holder 61 is recessed substantially throughout its height so as to receive and permit vertical and horizontal adjustment of the vise jaw members 66 and 67, respectively. In order to prevent springing or wobbling of the jaw 66 when subjected to pressure the vertical projections or shoulders 40 45 68 and 69, respectively, are provided for a snug sliding contact with the front and rear faces, respectively, of the body portion 61. Guide block 70 is machined U-shaped and looks over the vertical extension of vise jaw 50 55 66 at rear of holder, being fastened to jaw 66 by pin 71 and screw 72.

The other extremity of member 66 terminates in depending bifurcated right angular portion 73 which is adapted to engage the 55 T-head 74 of the integrally formed lateral coil supporting shelf or anvil extension of the body portion 61 which also supports the 60 65 slidable member 67, the said member terminating in an upward extension 75 extending through a slot in the member 66 and the lateral lugs 76 which with the extensions 75 forms the vise face of the member 67 and also limits the retractile movement of the said member. The member 67 is internally 65 threaded to receive the threaded adjusting

screw 76 provided with collar 77 secured as at 78 and bevel disc 79 adapted for engagement with the beveled portion of the pressure screw 80 carried by guide block 70 and which may be locked in any desired position 70 by lock screw 81. The free extremity of screw 76 is provided with operating knob or hand-wheel 82. The said member 67 is centrally slotted to receive retaining pin 83 secured to the body 61 by taper pin 84. 75

Secured to the upper vise member 66 by taper pin 85 is the perpendicular rack 86 adapted to mesh with the pinion 87 carried by the upper end of body portion 61 and operable by handle 88 to raise and lower the 80 said member 66. In order to lock the member 66 in clamping position when the rack 86 is down, a yoke 89 hingedly secured to the top of body portion 61 as at 90 and carrying lock screw 91 provided with operating 85 knob 91' for locking rack 86 in depressed position when the yoke has been brought directly over same. The said yoke assumes operative position through the instrumental-ity of coil springs 92 secured to the said yoke 90 as at 93 and to the holder 61 as at 94.

Positioned on the front angle bar 23 adjacent one of the holders 61 is the slidable loop gauge 95 comprising a triangular frame 95 formed with spaced upstanding ears 96 apertured to receive loop gauge pin 97 carrying operating handle 98. Mounted on the said pin 97 intermediate the said ears 96 is the compression spring 99 with one end seating against the washer 100 formed with slots 100 101 in which are adapted to selectively seat key pin 102 which determines the angle of adjustment of the gauge pin 97. The frame 95 is secured to the angle bar 23 similarly to holders 61 by locking screw 103 with its inner end carrying gib 104 and its outer end provided with operating knob 105. The loop gauge 95 like the coil holders 61 is adjustable on angle bar 23 according to graduations thereon. 110

Operation.

The operation of the machine constructed as above described, is as follows:

The holders 61 are properly positioned according to the graduations on longitudinal bars 23 and 23' in view of the type of armature winding desired, and the said bars are brought to closed position. The proper number of wires having been wound into a loop or coil B, the lower side of which is first placed in and gripped by the front holders and properly gauged by loop gauge 95 for location, that is, the gauge pin 97 is adapted to extend through the end of the loop and when coil has thereby been properly gauged the said pin is pulled forward which removes it from the loop permitting it to drop downward out of the way. Then the rear holders carried by bar 23' being slightly 120 125 130

higher than the front holders so that their vise members are adapted to overlie those of said front holders, are adapted to be clamped on the upper portion of said coil, 5 after which the right and left hand knuckle holders A are adapted to clamp the loop ends of the coil which is effected by placing the loop ends over the horn or hook members 56 of the plates 50 and clamped between the 10 plates 50 and 51 by the proper adjustment of adjusting screws 54 and T-head bolts 58, whereupon the loading operation is complete and the machine is then ready for the spreading operation which is effected by the manual 15 downward operation of pedal 10 which depresses bar 9 attached to pull rods 8, which, through the instrumentality of links 29 attached to arms 20 and 20' oscillate the same outwardly together with the longitudinal bars 23 and 23' with their respective holders 61, spreading the coil loop B firmly gripped by the said holders to conform to the desired configuration C shown in Fig. 15 of the drawings, the rear bar 23' being automatically 20 lowered to rest on stop collars 26 when the bars have reached their limit of separation, through the instrumentality of rods a which have their upper ends connected to said bar 23' and their lower ends to swivel bearings d secured to swivel bearings d attached to pedal bar 9.

The said collars 26 are so located in the set-up of the machine that in open or spread position the lower side of rear half of coil 35 will be at the same radius from center of rotation as the top side of front half of coil. The center of rotation thus represents the center of motor for which the coil is being made, and the respective positions of the slot 40 portions of the coil are then at exactly the same distance from the center of rotation that they occupy when inserted in the motor, and the action of the machine insures that the proper pitch or angle will be produced 45 on these portions of the coil.

When the pedal is released the pedal bar 9 is returned to normal position by the springs 16 and the bar 23' is automatically elevated so that the holders 61 carried thereby will overlie the holders carried by bar 23 when they again assume loading position.

While the oscillating arms 20 and 20' and bars 23 and 23' are in open or spreading position the knuckle "kick up" or end loop forming attachment may be elevated or lowered to provide the proper angle of the end loops with respect to the body of the coil, which as above stated, may be accomplished during the spreading operation, after which the 55 holders and knuckle members may be loosened and the finished coil removed, whereupon the machine may be returned to loading or closed position as in the first instance.

65 I have described broadly the operation of

the machine forming the subject matter of this invention, and as the operation of the various parts is thought to be clear from the detailed description, further explanation is deemed to be unnecessary.

70 Although in my previous invention, namely, Patent No. 1,297,998, was a step in advance of the art, nevertheless, after much practice and experimentation I have evolved certain refinements enabling simpler and 75 more accurate adjustment of parts including the manner of adjusting the angle bars 23 and 23', the manner of constructing the oscillating arms, the improved loop end or 80 knuckle holder structure, increasing the adjustability and improving the structural design of the coil holders, and have added other important features, such as the "kick up" attachment for properly shaping the 85 loop ends, and the automatic adjustment of the top or rear bar 23' with respect to the front bar 23, and thereby have evolved a coil shaper or spreader eliminating the deficiencies of those heretofore in use, of great 90 adaptability, efficient to operation, and yet 95 manufactureable at a reasonable cost.

In practice, I have found the form of my 100 invention illustrated in the accompanying drawings and referred to in the above description, as the preferred embodiment is the most efficient and practical; yet realizing the conditions concurrent with the adoption of my machine will necessarily vary, I desire to emphasize that various minor changes in details of construction, proportion and arrangement of parts, may be resorted to within the scope of the appended claims without departing from or sacrificing any of the principles of this invention.

Having thus described my invention, and 105 without enumerating variations and equivalents, what I desire protected by Letters Patent is as set forth in the following claims:

110 1. A coil shaping machine comprising means for gripping the ends of a wire coil loop, a plurality of means for gripping and holding each side of the loop, operating means for simultaneously moving the holding means on the respective sides away from or towards each other; of means cooperating with the operating means to raise and lower the 115 holders on one side of the loop with respect to the holders on the other side.

120 2. A coil shaping machine including a bed structure, oscillating arms carried by said structure, means connecting the opposing pairs of said arms, said means carrying a plurality of coil holders, end coil loop holders or knuckle forming members, manually operated means carried by said bed structure for oscillating the said arms and their respective connecting means, the said manually operated means also simultaneously and automatically effecting vertical adjust- 125 130

ment of the holders on one side of the loop with respect to those on the other.

3. A coil shaping machine comprising a bed structure, oscillating arms carried by the said bed structure, longitudinal bars connecting the opposing pairs of said arms, a plurality of holders carried by said bars for holding the loop ends of a wire coil, operating means for simultaneously moving the bars and their respective holders away from and towards each other; of means cooperating with the operating means for simultaneously raising and lowering one of the bars with respect to the other bar during the spreading operation.

4. A coil shaping machine comprising bed structure, oscillating arms carried by said bed structure, longitudinal bars connecting the opposing pairs of said arms slidably adjustable thereon, a plurality of holders carried by said bars, operating means for simultaneously moving the bars and their respective holders away from and towards each other; of means simultaneously cooperating with the operating means for raising and lowering one of the bars with respect to the opposite bar during the spreading operation.

5. A coil shaping machine comprising a bed structure, a center bar carried by said structure, a pair of coil loop end gripping means slidably mounted on said bar, oscillating arms rotatably carried by said rod, longitudinal bars connecting the opposing pairs of said arms, a plurality of coil holders slidably adjustable on said bars, operating means for simultaneous outward and inward oscillation of the respective arms and bars, additional means simultaneously operable by the operating means for raising and lowering the top or rear bar with respect to the opposite or front bar during the operation of the machine.

6. A coil shaping machine comprising a bed structure, a center bar carried by said structure, vertical supporting rods longitudinally adjustable on said bar, coil loop end gripping members or knuckle holders carried by said rods and adjustable thereon, oscillating arms rotatably carried by said center bar, angle bars connecting the opposing pairs of said arms, coil holders carried by each of the angle bars, operating means for simultaneous actuation of the said arms carrying the respective angle bars towards and away from each other; of means coacting with and operable by the operating means for raising and lowering during the closing and spreading operations, respectively, one of the angle bars with respect to the other.

7. A coil shaping machine comprising a bed structure, a center rod carried by said structure, vertical supporting rods adjustable on said center rod, coil loop end clamping members or knuckle holder structures, means

carried by the said rods coacting with means carried by the holder structures for effecting vertical adjustment of the said holder structures, a plurality of means for gripping and holding each side of a coil loop, operating means for simultaneously moving the holding means on the respective sides away from or towards each other.

8. A coil shaper comprising a bed structure, a longitudinal center rod carried by said structure, vertical supporting rods adjustably carried by said center rod, coil loop end clamping member or knuckle holder anchoring elements adjustably mounted on said supporting rods, coil loop end clamping members or knuckle holders rotatably adjustable on said anchoring elements, said knuckle holders embodying complementary clamping plates parallelly adjustable with respect to each other, one of said plates being provided with means for insertion in the end loop of the coil, a plurality of means for gripping and holding each side of a coil loop, operating means for simultaneously moving the holding means on each side of the loop away from or towards each other.

9. A coil shaping machine comprising means for gripping the ends of a wire coil loop, a plurality of holders for gripping and holding each side of the loop, each of said holders embodying a pair of adjustable vise or gripping jaws, means for effecting relative vertical and longitudinal adjustment, respectively, of the said jaws and means for locking the said jaws in clamping position, operating means for simultaneously moving the holders on the respective sides of the loop away from or towards each other; of means cooperating with the operating means to raise and lower the holders on one side of the loop with respect to the holders on the other side.

10. A coil shaping machine comprising a supporting structure, means carried by said structure for gripping the loop ends of a wire coil, said means being longitudinally, vertically and rotatably adjustable with respect to said coil, a plurality of holders for gripping and holding each side of the loop, said holders being longitudinally and vertically adjustable with respect to the said loop, operating means for simultaneously moving the holders on the respective sides of the coil towards or away from each other, means cooperating with the operating means for raising and lowering the holders on one side of the loop or coil with respect to the holders on the other side.

11. A coil shaping machine comprising adjustable means for gripping and holding the end loops of a wire coil, a plurality of coil holders for gripping engagement with each side of the coil and vertically and longitudinally adjustable with respect thereto, of means for gauging the distance of inside of

- loop from holder obviating the necessity of adjusting the holders of each coil, operating means for simultaneously moving the holders on the respective sides of the coil towards or away from each other, and means cooperating with the operating means to raise and lower the holders on one side of the coil with respect to those on the other side.
- 10 12. A coil shaping machine comprising a supporting structure, a center bar carried by said structure, a pair of vertical supporting rods slidably mounted on said bar, an upright frame structure carried by the supporting structure carrying depending coil springs attachable to the upper ends of the supporting rods for maintaining the said rods in vertical position at any desired longitudinal adjustment on said center rod,
- 15 15. loop end gripping members or knuckle holders carried by the vertical supporting rods, a plurality of holders for gripping and holding each side of the coil, operating means for simultaneously moving the hold-
- 20

ers on the respective sides towards or away from each other, of means coacting with the operating means for raising and lowering the holders on one side of the coil with respect to the holders on the opposite side.

13. A coil shaping machine comprising a supporting structure, oscillating arms carried by said structure, longitudinal bars connecting the longitudinally opposed pairs of said arms slidably adjustable thereon, a plurality of coil holders carried by said bars, end loop holders or knuckle forming members, means for effecting vertical and rotatable adjustment of said knuckle holders with for simultaneously moving the bars and their respective holders towards and away from their respect holders towards and away from each other, and additional means cooperating with the operating means for raising and lowering one of the bars with respect to the opposite bar during the spreading operation.

SAMUEL H. BROWNING.
